UNITED STATES PATENT OFFICE.

HOWARD TERHUNE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

MEANS FOR OPERATING THE ROLLS OF A BOARD DROP-HAMMER.

1,246,185.

Specification of Letters Patent.

Patented Nov. 13, 1917.

Application filed June 26, 1916. Serial No. 105,871.

To all whom it may concern:

Be it known that I, HOWARD TERHUNE, a citizen of the United States, and a resident of Chambersburg, in the county of Franklin 5 and State of Pennsylvania, have invented certain new and useful Improvements in Means for Operating the Rolls of Board Drop-Hammers, of which the following is a specification.

10 My invention relates to an improved means for carrying the operating rolls of a board drop hammer and the object of my invention is to furnish an improved housing for carrying the board operating rolls of a 15 drop hammer the several parts of which will be reduced to their simplest form and which will be so constructed that it may be quickly taken down to permit the instant removal of the shafts and rolls or other parts which 20 may need attention or repairs.

My invention is illustrated in the accompanying drawings in which similar letters of reference indicate similar parts throughout the several views, and in which—

25 Figure 1, is a side elevation of the housing carrying the shafts and rolls of a board drop hammer, and

Fig. 2, a front elevation, partly in section, of Fig. 1.

30 3—4 are the driving pulleys for actuating the shafts 5—6 which carry the rolls 7—8 of a board drop hammer. 9 is the board which is attached to the ram, and 10—11 the housings which inclose the rolls which operate to 35 elevate the board and in which are formed the bearings for the shafts of said rolls.

Heretofore, as far as I am advised, it has been the practice to cast the holder or housing which carries the board elevating roll, 40 its shaft, etc., in one piece and it has often been very difficult to remove the shaft from a roller while in the housing for the shaft and its roll must necessarily fit closely and not infrequently considerable force is necessary to take them down.

As the rolls 7—8 have to be moved toward and away from one another in order to engage and disengage the board 9 each roll is carried in a separate housing but as one of 50 these parts is the duplicate of the other but one will be described, and as this invention

has to do with the roll carrying housings only, no attempt will be made to describe the means whereby the rolls are operated to engage and disengage the board.

55

My rolls 7—8 are secured to or cast with their shafts 5—6 concentrically and, as usual, rotate in opposite directions. The housings for the rolls and shafts are split at right angles to the shafts forming two separate pieces 11 and 12 and these pieces are, preferably, furnished with a tongue and groove 13 in order that their alinement may be insured when they are bolted together.

60 In the drawings the housing is shown split in the middle but, of course, this splitting may be nearer one end than the other, or otherwise, as may be found most convenient for the purposes intended.

65 It will be evident that my housing for the roll carries with it extensions which are inclosed within outer bearings for adjustment purposes so that the roll can be moved toward and from the board and that at the same time these extensions surround the roll 75 shaft bearing.

Having thus described my invention, I claim as new and desire to secure by Letters Patent:—

1. A housing for an elevating roll and its 80 shaft for a board drop hammer, comprising two parts abutting in a plane at right angles to the roll carrying shaft and bearing members for board gripping adjustment purposes inclosing the ends of the housing. 85

2. A housing for an elevating roll and its shaft for a board drop hammer, carrying one of the coöperating members for adjustment of the roll toward and from the board and a bearing for the roll shaft, and comprising two parts abutting in a plane at 90 right angles to the roll carrying shaft.

3. A housing for an elevating roll inclosing both the roll and its shaft, providing bearings for opposite ends of the roll shaft 95 and transversely divided into two parts between these bearings.

4. A housing for an elevating roll and its shaft for a board drop hammer, comprising a pair of bearings, one for each end of the 100 shaft and a casing for the roll of larger diameter than said bearings and divided trans-

versely to the shaft in this larger diameter portion of the housing and coöperating means between the two parts maintaining them in axial alinement.

5. A housing for an elevating roll and its shaft for a drop hammer comprising two bearings, one for each end of the shaft and

a connecting roll cover transversely divided and interfitting at the point of division.

HOWARD TERHUNE.
